(57) **ABSTRACT**

A shelf frame for a rack of shelves includes an elongated body; a ledge extending perpendicularly from a bottom edge of the elongated body, the ledge having a width equal to a height of the elongated body; an elongated enhancement disposed along a top edge of the elongated body, the enhancement being bent toward the ledge; two upright extensions disposed at two ends of the elongated body respectively; and a plurality of fasteners disposed in each of the two upright extensions. The two upright extensions and the elongated body are on the same plane. Each of the two upright extensions has a length equal to twice of the height of the elongated body.

FIG. 3

FIG. 4

FIG. 5

FIG. 6

FIG. 7

SHELF FRAME FOR A RACK OF SHELVES

BACKGROUND OF THE INVENTION

1. Field of the Invention

The invention relates to racks of shelves and more particularly to a shelf frame for a rack of shelves in which in a first mode the shelf frames are mounted on four sides of a shelf of the rack of shelves and are capable of decreasing the possibilities of articles falling, and in a second mode the shelves are easy to hold into position or the articles are easy to place on the shelf.

2. Description of Related Art

Adjustable racks of shelves are widely used in stores due to their easy assembly and sufficient structural strength. Further, a height of the rack of shelves can be easily adjusted based on applications. A shelf is mounted on four shelf frames prior to placing articles thereon.

However, shelves may not be accommodated to mount on the shelf rack. Thus, cutting of the shelves is required. Further, the shelves may slide in assembly. Furthermore, articles placed on the shelves may fall and be damaged if sufficient care is not taken.

Thus, the need for improvement still exists.

SUMMARY OF THE INVENTION

It is therefore one object of the invention to provide a shelf frame for a rack of shelves, including an elongated body; a ledge sticking inward from the elongated body and being perpendicular to the elongated body, the ledge having a width equal to that of the elongated body; an elongated enhancement disposed along an edge of the elongated body and being distal from the ledge, the enhancement being bent toward the ledge; two upright extensions disposed at two ends of the elongated body respectively; and a plurality of fasteners disposed at the extensions opposite to the ledge; wherein the extensions and the elongated body are on the same plane and are parallel to each other; and wherein the extension has a length equal to twice of the width of the elongated body.

Preferably, in a first mode of mounting the shelf frames on the rack of shelves, the extensions are downward mounted on the rack of shelves. A shelf is mounted on the ledges and the elongated body serves a raised limit member. Thus, the shelf is prevented from projecting out of the rack of shelves due to vibration. Further, articles placed on the shelf are prevented from falling.

Preferably, in a second mode of mounting the shelf frames on the rack of shelves, the extensions are upward mounted on the rack of shelves. A shelf is mounted on the shelf frames and articles can be placed on the shelf. The ledge has a width equal to that of the elongated body and the extension has a length equal to twice of the width of the elongated body. A user may mount the shelf frames in a mixed mode depending on applications. A shelf is mounted on the ledges and there is no significant height difference between the shelf and the ledges.

The enhancement can increase the structural strength of the elongated body and prevent the hand of a user holding the shelf frame from being hurt.

The above and other objects, features and advantages of the invention will become apparent from the following detailed description taken with the accompanying drawings.

BRIEF DESCRIPTION OF THE DRAWINGS

FIG. 1 is a perspective view of a shelf frame for a rack of shelves according to the invention;

5 FIG. 2 is another perspective view of the shelf frame; FIG. 3 is a side elevation of the shelf frame;

FIG. 4 is a top view of the shelf frame;

10 FIG. 5 is a perspective view of the four shelf frames mounted on a shelf of a rack of shelves in a first preferred embodiment;

FIG. 6 is a perspective view of the four shelf frames mounted on a shelf of a rack of shelves in a second preferred embodiment; and

15 FIG. 7 is a perspective view of the four shelf frames mounted on a shelf of a rack of shelves in a third preferred embodiment.

DETAILED DESCRIPTION OF THE INVENTION

Referring to FIG. 1, a shelf frame 10 for a rack of shelves in accordance with the invention comprises an elongated body 11, a ledge 12 extending perpendicular from a bottom edge of the elongated body 11, the ledge 12 having a width equal to the height of the elongated body 11, an elongated enhancement 13 extending along a top edge of the elongated body 11 and being distal from the ledge 12, the enhancement 13 being bent toward the ledge 12, two upright extensions 14, extending from each of two ends of the elongated body 11 respectively, and two cuts 15, each cut disposed between an end of the ledge 12 and the respective extension 14. Each corner of the ledge 12 and the extension 14 is curved for the purpose of preventing the hand of a user holding the shelf frame 10 from being hurt.

35 The ledge 12 has a width equal to the height of the elongated body 11 and the extension 14 has a length equal to twice of the height of the elongated body 11. For the rack having the same height, regarding the shelf frame 10, a horizontal height of the ledge 12 is irrespective of downward assembly of the extensions 14, upward assembly of the extensions 14, or a combination thereof. In other words, the extensions 14 and the elongated body 11 of any shelf of the rack are on the same vertical plane.

40 Referring to FIG. 2, the extensions 14 and the elongated body 11 are on the same vertical plane. A plurality of fasteners 16 are provided at the extensions 14. The fastener 16 includes a neck 161 and a head 162 having a diameter greater than that of the neck 161.

45 Referring to FIGS. 3 and 4, the enhancement 13 has a predetermined thickness after being bent. Thus, the enhancement 13 can increase the structural strength of the elongated body 11 for support.

50 Referring to FIG. 5, in a first preferred embodiment a rack of shelves having four posts 20 are shown in which the ledge 12 of each of the four shelf frames 10 is mounted on a bottom of the shelf frame 10, and a top of the elongated body 11 has an elevation greater than that of the ledge 12 so that the elongated body 11 can serve as a raised limit member.

55 Referring to FIG. 6, in a second preferred embodiment a rack of shelves having four posts 20 are shown in which the ledge 12 of each of the four shelf frames 10 is mounted on a top of the shelf frame 10, and a top of the elongated body 11 has an elevation equal to that of the ledge 12. Thus, the elongated body 11 cannot serve as a raised limit member.

60 Referring to FIG. 7 in conjunction with FIG. 3, in a third preferred embodiment a rack of shelves having four posts 20 are shown in which the shelf frames 10 are mounted on the

rack of shelves in a mixed mode. In detail, the extensions **14** of two shelf frames **10** are downward mounted on the rack of shelves, and the extensions **14** of the other two shelf frames **10** are upward mounted on the rack of shelves. The fasteners **16** are used to secure the shelf frames **10** to the posts **20**. The ledge **12** has a width equal to the height of the elongated body **11** and the extension **14** has a length equal to twice of the height of the elongated body **11**. Thus, the extensions **14** and the elongated body **11** of any shelf of the rack are on the same vertical plane. A shelf **21** is mounted on the ledges **12** and there is no significant height difference between the shelf **21** and the ledges **12**. A plurality of articles **221** are placed on the shelf **21**. It is possible to push the articles **221** through the shelf frames **10** because the shelf frames **10** do not serve as a limit member. This has the advantage of being able to place the articles **221** on the shelf **21** or pushing the articles **221** on the shelf **21**. Another article **222** is also shown placed on the shelf **21** and is limited by both the elongated body **11** and the enhancement **13**. Thus, the article **222** is prevented from falling. It is envisaged by the invention that a user may mount the shelf frames **10** in the mixed mode depending on a desired application.

While the invention has been described in terms of preferred embodiments, those skilled in the art will recognize that the invention can be practiced with modifications within the spirit and scope of the appended claims.

What is claimed is:

1. A shelf frame for a rack of shelves, comprising:
 an elongated body;
 a ledge extending perpendicular from a bottom edge of the elongated body, the ledge having a width equal to a height of the elongated body;
 an elongated enhancement disposed along a top edge of the elongated body and being distal from the ledge, the elongated enhancement bent toward the ledge;
 two upright extensions disposed at two ends of the elongated body respectively; and
 a plurality of fasteners disposed in each of the two upright extensions, wherein each of the plurality of fasteners includes a neck and a head, the head having a diameter greater than that of the neck;
 wherein the two upright extensions and the elongated body are on the same plane, and
 wherein each of the two upright extensions has a length equal to twice of the height of the elongated body.

2. The shelf frame for a rack of shelves of claim 1, further comprising two cuts, each cut disposed between an end of the ledge and one of the two the upright extensions, respectively.

3. The shelf frame for a rack of shelves of claim 1, wherein the ledge and the two upright extensions each have curved corner edges.
